UNITED STATES PATENT OFFICE

WILLIAM Y. ALLEN, OF BERKELEY, CALIFORNIA

APPLICATOR FOR DISPENSING LIQUIDS FROM CONTAINERS

Application filed July 30, 1928. Serial No. 296,128.

This invention relates to improvements in applicators for dispensing liquid from containers. More particularly it provides a cap for a container, in which container-closing means is combined with dispensing and applying means for liquid contents, using the container as a handle. A principal utility of the invention is for liquids desired to be deposited on a surface in limited quantity, or to be spread over it or rubbed into it, as a volatile cleansing liquid on a fabric. But the invention can serve also as a self-feeding device for applying any of various liquids, and for various purposes.

15 It is an object of the invention to provide so that the closure cap, which ordinarily seals the mouth of the container, may, by a simple operation, be converted into a convenient and efficient device for gradual application of liquid contents of the container to a surface which is being treated. This transformation is accomplished by an interior snap disk for the cap, normally tending to remain always within the cap as a closure-washer, but having a handle for disengaging it when the liquid-dispensing operation through the cap is wanted, and for replacing it when the container is to be sealed tight.

The applicator provides so that in addition to being merely sopped on, the liquid may be gently wiped over the surface as with a soft flexible brush, or may be stiffly rubbed into the material to which it is applied. In the case of cleaning liquids applied to fabrics, the liquid may thus be passed completely through the material, taking up foreign matter and depositing it according to approved practice on a suitable absorbent "backer" which may be a blotter.

40 These results follow from the relative shape and arrangement of a laminated felt applicator tip, and the clamping means by which this tip is held on the cap. The laminæ of the felt tip have their planes parallel to certain rectilinear clamping jaws of metal, by which they are held tightly in a transverse plane or zone of compression between the two straight-line jaws. About this zone the projecting part of the tip can oscillate rather freely in a brushing action, somewhat as on

a hinge, with the flexible nature of the laminæ and the relative looseness of their fibrous connection to each other utilized to the full. Perpendicular these jaws and crossing the laminæ perpendicularly are other inturned clamping edges of metal, about which the tip can oscillate only with more difficulty and stiffly, more as when one rubs with a block.

55 The invention also provides so that the felt applying device can be compact enough at the neck where it is clamped to insure slow feed of liquid, its laminæ being there closely matted while the outward portion is rather freely flexible.

60 Thus structural features of felt and of clamp are made to cooperate; and it is moreover a feature that by reason of the rectilinear edges the combined device embodies a very simple and economical structure of each of its elements, which makes it inexpensive to manufacture, yet convenient, efficient and practical for a variety of uses.

65 The particular cap illustrated is adapted to be screwed over the mouth of a can or other container, although it might be otherwise fastened; and the cap carries two pairs of jaws, acting cross-wise of each other on the base edge portion of a mass of felt which they hold on the cap.

70 These jaws are plate projections of sheet metal bent up from a base secured to the cap, are inclined inward as they rise, and have their edges turned further inward, like claws. The felt mass may be made by cutting a rectangular piece from a suitably thick piece of laminated felt. The jaws of the broader pair are set in against the felt in the direction of the thickness of the original sheet. Their edges therefore extend parallel to the planes of the laminæ; and they compress the laminæ strongly together in a straight zone, with what is herein called a "hinge grip." The main part of the felt laminated mass projects from the cap considerably beyond this pair of straight edged jaws; and the projecting portion is freely flexible as on a hinge about the zone where it is thus compressed, and thus produces easy brush action which is uniform along the whole of the hinge line.

The other pair of jaws are sunk into the edges of felt at the ends of the said hinge line. These extend across the thickness of the laminae; and they hold the felt with the relatively less flexibility which characterizes the laminae when effort is made to bend them in the direction in which the laminar planes extend. And this grip is herein called the "block grip" as distinguished from the "hinge grip" of the first mentioned pair of clamping jaws.

These two pairs of plate jaws may be integral parts of the same piece of sheet metal; but a deep cleft exists between each plate jaw and the adjacent jaw of the other pair.

Within the top the usual gasket may be employed, but a small central perforation extending through the gasket and through the metal top of the cap and metal base of the jaws provides for passage of liquid to the felt mass beyond. The edges of tinned iron thus denuded by the puncturing might rust; but the setting of a brass eyelet in this perforation prevents the passing of rust which otherwise might seep through and stain a fabric on which the applicator is being used, by housing the denuded edges in brass, and at the same time it secures the cap and jaw-base together.

Closure means for this hole consists of a flexible, elastic, imperforate, oversize disk. The fit is such as to produce a snap action in passing the screw threads; and this disk has a protruding central stem, constituting a handle by which the insertion and removal of the disk is accomplished. This stem has another function when the disk is out, for it helps keep the disk clean, keeps it in sight, and helps in picking it up. When the disk is set into the cap, and the latter is screwed on a container, liquid contents are sealed tight against escape. When the cap is removed, contents can be poured out as usual; or, upon removing the cap, extracting the closure disk from it, and replacing the cap, and using the container as the handle of an applicator, the liquid can pass through the cap into the felt and by that can be sopped out without rubbing; or can be gently spread over a surface as by a brush, by moving the tip to and fro about its hinge line; or can be rubbed into the material being treated, by moving it to and fro in the direction of said hinge line.

It is intended that the patent shall cover, by suitable expression in the appended claims, whatever features of patentable novelty exist in the invention disclosed.

In the accompanying drawings:

Figure 1 is an elevation showing the invention embodied in a container, viewing it on the side of the broad jaws and in the direction of movement for brush or hinge action;

Figure 2 is an elevation, in section on line 2—2 of Figure 1, being seen in the direction of movement for block action, although show-

ing the container sealed by presence of the closure disk;

Figure 3 is a view on the same section as in Figure 2, but with the closure disk removed from the cap, and showing the device in use for dispensing with brush action;

Figure 4 is a plan of the container with the felt mass removed; and

Figure 5 is a perspective of the closure disk, enlarged.

Referring to the drawings, the container 10 which may be of sheet metal, glass or other suitable material, has its neck 12 screw-threaded to receive the screw-cap 14 which is provided on its plane upper face with two pairs 16, 17 of plate jaws, rectangularly arranged. As illustrated, each jaw is a plate of sheet metal integral with, and standing up from, a base 15. Each plate is inclined inward and has its top edge bent abruptly inward making its straight upper edge a sort of claw of substantial length. The plates 16, whose compressing of the felt makes the "hinge grip", are somewhat broader than the plates 17 whose compressing of the felt makes the "block grip." As a whole they effect a tight gripping of the block 18, of felt or other suitable fibrous material. The felt has a laminated structure. It is arranged on the cap 14, within the clamping jaws 16, 17, so that standing on the base 15 the laminae extend vertically and run parallel to the jaws 16, with a substantial portion of the whole mass projecting beyond the jaws 16, 17.

Being approximately rectangular this mass may be cut without waste from a sheet of felt of suitable thickness. The setting of the jaws 16, 17 into its sides and ends gives it the shape shown. The hinge jaws 16 may be set into it to varying degrees according to the liquid which is to be dispensed, or according to desire, so as to make the zone at the hinge line be more or less tightly compacted to control the rate of outflow of liquid.

The laminae of the felt being to a restricted extent independent of each other, due to the fibres in any lamina being more loosely connected to fibres in a neighboring lamina than to fibres in their own lamina, the mass as a whole acts freely flexible when pressed in direction to bend it about the straight edges of the plate jaws 16, very much as bristles slip over each other when a paint brush is used. But when pushed as if to bend about the block grip edges 17, the stiffest dimension of each and every lamina resists the bending, aided by the stiffness of the plates 16, whose grip is such as to prevent the bases of the laminae from being displaced. This gives the "block action" for rubbing stiffly on a surface. The deep clefts between plates 16 and plates 17 permit the hinge effect to extend close to the end; and the relatively shorter extent of the block grip jaws 17 minimizes the restrictive effect which these

plates might have upon the bending about the straight edges of plates 16.

Within the cap 14 the usual gasket 20 may be employed, but a small central perforation 22, which extends through the top of the cap, extends also through the gasket to provide a passage for liquid from the container to the felt mass. When the container is not in use as a dispenser of liquid, this passage 22 is to be closed by an imperforate elastic disk 24 which is of such size and material, for example of celluloid, as to snap into the cap and be held therein by the threads thereof, when the cap is off; and when the cap is on, to be compressed between the gasket 20 and the bottle top. A stem 26 on the disk 24 affords a permanent leverage for prying it out of the cap, and for handling this disk when removed. This may be a simple rod of celluloid stuck endwise to the disk, by application with a celluloid solvent, as acetone.

In its use for sealing the mouth of a container the disk 24 will be in position within the cap, as seen in Figure 2. It is so thin and flexible that the gasket exerts its sealing effect through this disk. When liquid is to be dispensed according to the invention, the cap is to be unscrewed from the container and the disk 24 pried out by its handle 26. It easily snaps out because of its resilience. Then the cap is to be replaced. The container is thus closed tightly by the gasket 20 except for the small opening 22 under the tightly constricted part of the felt. When the can is inverted its liquid contents can pass through the passage 22 to the felt of the applicator, and under the working to and fro of fibres a sufficient quantity of air can pass reversely, and thus the contents can be applied to the material being treated either as by a flexible brush, or by rubbing as with a block of felt.

The disk 24 can be made distinctive, for recovering it after being out of use, by making the handle of a distinctive color, as red, while the disk proper is white. The resilient material and slight oversize of the disk provide against its dropping out and becoming lost when the cap is removed.

The feed opening 22 goes through the gasket 20, the cap 14 and the plate 15, which comprises the base of the device 16, 17, for holding the dispensing felt. The plate 15 may be secured on the top of the cap by the inserting of an eyelet 23, on the axis of this opening. Rigidity of the plate, holding the application tip of felt during rubbing, to avoid its rotation relative to the cap, may be attained as here illustrated by providing one or more other eyelets 25, inserted at the same time, clamping the base 15 to the top of cap 14. Ordinarily one such is sufficient, although three are here illustrated; while if preferred solder or other securing means may be employed. Being covered by the gasket 20, the eccentric eyelets 25 do not permit

escape of liquid additional to that which flows out through the axial eyelet 23. And the rate of outflow through this eyelet may be so retarded by the tightness of compression of the felt by the jaws 16 that even when the container is used to hold a volatile liquid the disk 24 can with safety be left out of the cap over intervals between periods of using the applicator. By the insertion of this disk and the screwing of the cap upon the container the closure is made complete and tight.

The applicator described may economically and satisfactorily be made as a tin can with tin cover or cap. In that case the tin plated iron becomes denuded where the puncture is made for the hole 22, and the raw edges are liable to corrosion, from which rust may be carried through by the liquid to the fabric which is being treated. But by making the eyelet 23 of brass the denuded raw edges of the iron become so housed between the flanges of the eyelet that their corrosion is delayed or prevented; and even if rust be present it is so housed within the brass that the outflowing liquid has no access to it.

I claim as my invention:

1. A dispensing cap for a liquid container, comprising a cap body adapted to be fastened over the mouth of the container, and having a portion overlying said mouth; a plurality of separate laminae of porous material assembled together to form a flexible, laminated, porous spreader mass on the outer face of the cap; and a removable and replaceable disk, adapted for arrangement within the cap and large enough to be engaged between container rim and cap; there being a small perforation in the face of the cap, opposite the mouth of the container, for restricted outflow of liquid to moisten said porous spreader mass; said disk constituting a closure adapted by its said removal to permit liquid supply to the spreader, and by its said replacement to arrest said supply, during inversion of the container and while said moistened spreader may continue to be manipulated in use.

2. A dispensing cap for a liquid container comprising a cap body adapted to be fastened over the mouth of the container, having a disk overlying the mouth, with a small perforation for restricted outflow of liquid; a gasket within the cap body, underlying its said disk, and with a perforation registering with the perforation in said disk, the said gasket constituting a tight closure except as to said perforation; and a removable and replaceable closure disk also within the cap, large enough to be compressed between container rim and gasket with sealing contact thereby closing access of contents to said perforation.

3. A dispensing cap for a liquid container comprising a cap body adapted to screw over the mouth of the container, having a

disk overlying the mouth, with a small perforation for restricted outflow of liquid; a gasket within the cap body, underlying its said disk, and with a perforation registering with the perforation in said disk, the said gasket constituting a tight closure except as to said perforation; a resiliently removable closure disk within the cap, being of resilient material slightly larger than and engaged 10 within the screw threads of the cap, and adapted to be compressed between the container rim and gasket with sealing contact thereby closing access of contents to said perforation; and a stem on the disk projecting 15 toward the mouth of the cap for snapping the disk out of and into its position of engagement within the cap.

4. A dispensing cap for a liquid container, comprising a cap body adapted to be fastened over the mouth of the container, having a disk portion overlying the mouth, with a small perforation for restricted outflow of liquid; a plurality of separate laminæ of felt assembled together to form a laminated 25 porous mass on the outer face of said disk portion of cap, with the laminæ set edgewise across the perforation in said disk; and clamping jaws for the felt on said outer face, comprising a pair having a grip with rectilinear edges parallel to the planes of said laminæ, and near the base edge of said mass, whereby the projecting parts of individual laminæ are freely flexible, and the projecting part of the mass as a whole bends easily 30 to and fro about the rectilinear edges of said jaws.

5. A dispensing cap for a liquid container, comprising a cap body adapted to be fastened over the mouth of the container, having a disk portion overlying the mouth, with a small perforation for restricted outflow of liquid; a plurality of separate laminæ of felt assembled together to form a laminated porous mass on the outer face of said disk 45 portion of cap, with the laminæ set edgewise across the perforation in said disk; clamping jaws for the felt on said outer face, comprising a pair having a grip with rectilinear edges parallel to the planes of said laminæ, and near the base edge of said mass, whereby the projecting parts of individual laminæ are freely flexible, and the projecting part of the mass as a whole bends easily to and fro about the rectilinear edges of said jaws; and another pair of jaws set with grip extending along a line perpendicular to the planes of 55 said laminæ.

6. A dispensing cap for a liquid container comprising a cap body adapted to screw over the mouth of the container, with a gasket, each having a hole constituting a dispensing perforation in the portion thereof which overlies the said mouth; a plate with clamping jaws on the outer face of said portion; an eyelet at the perforation, securing plate

and cap together; a plurality of separate laminæ of felt assembled together to form a flexible, porous mass gripped by said jaws so as to stand close against said overlying portion of the cap and across the 70 said eyelet; the jaws being arranged with rectilinear edges extending parallel to the planes of the laminæ, at which edges the felt is tightly compressed, and about which edges the felt bends freely; a second eyelet, securing plate and cap against relative rotation about the first eyelet; a removable closure disk adapted to close said perforation thereby to seal the mouth of the container during inverted manipulation of the laminar felt in 80 spreading, and at times of non-use; and a handle on said disk for removing and inserting it within said cap.

Signed at Boston, Mass., this 27th day of July, 1928.
